(57) **CLAIM**

The ornamental design for table, as shown and described.

DESCRIPTION

1.1 is a top perspective view of a table, showing my new design;

1.2 is an end view thereof, the opposite end being a mirror image thereof;

1.3 is a side view thereof, the opposite side being a mirror image thereof;

1.4 is a top view thereof; and

1.5 is a bottom view thereof.

The broken lines shown in the drawings of the table are for the purpose of illustrating the environment and form no part of the claimed design.
